LOUD SPEAKER DEVICE

Hans Wittorf, Erfde, Germany

Application July 31, 1930, Serial No. 472,074
In Germany August 7, 1929

4 Claims. (Cl. 179—114)

This invention relates to a loudspeaker system which is characterized by the arrangement of a freely oscillatable multiple armed armature rotatable around a pivot axle.

Such loudspeaker systems are known, wherein, for example, the coils conducting the alternating current are fitted on the poles or on the armature. The objection of such a construction is chiefly that the armature system does not pass out of the field range of the magnets and also cannot move at right angles to the magnetic lines of force; the armature likewise does not always automatically come into its inoperative position without external additional forces. Moreover, the fitting of the known systems is complicated and has too large masses. All these properties exert a detrimental influence on the sound production as regards timbre and volume of sound.

The invention avoids these objections substantially in that the armature consists of arms distributed like wheel spokes around the common pivot axle and arranged with a small air gap between the middle and edge surfaces of two coaxial pot-shaped pole pieces each connected to an arm of a permanent horse-shoe magnet. The middle and edge surfaces of these pole pieces are so constructed that a number of tooth-like projecting poles corresponding to the number of armature arms are produced, the teeth opposite one another in the middle and edge zones of the two pole pieces being, however, mutually displaced so that a tooth of the middle zone on one side is covered by its coordinate armature arm, whereas the corresponding tooth of the outer zone is covered from the other side by the armature arm, and coils leading the talking current are accommodated one in each of the free spaces of the pot-shaped pole pieces coaxially to the armature in the pole pieces. The control is effected in such a manner that, according to the direction of the alternating flux the force flux produced by the permanent magnet is amplified at the middle surface of the pot-shaped pole pieces and at the same time attenuated at the outer surfaces or inversely, so that the armature performs rotary movements in one direction or the other and when no alternating current is flowing returns into its medial position under the action of the permanent attraction.

The tooth-shaped projecting poles of the middle and edge surfaces both of the pot-shaped poles and also of the two differently polarized pole shoe pieces are opposite and their coordinate armature arms are so bent that in position

of rest they cover on one side the tooth-shaped projecting poles of the middle pole surfaces, and on the other side the tooth-shaped projecting poles of the edge surfaces.

An embodiment of the invention is illustrated by way of example in the accompanying drawing in which:

Figure 1 is a longitudinal section showing a loud-speaker system with permanent horse-shoe magnet with coils arranged between its arms;

Figure 2 is a top plan view of Figure 1, with one arm of the magnet removed;

Figure 3 is a perspective view of the magnet system.

The armature is composed of radial arms *a* rotatable around a common axle *f* and mounted between two pot-shaped pole pieces connected by a ring *e* and arranged between the two arms of a horse-shoe magnet *g*. The two pot-shaped pole pieces have tooth-like projections *c* near their middle portion and similar projections *b* near their periphery. These middle and circumferential projections are mutually displaced so that the armature arms *a* only cover the projections *b* from one side and the projections *c* from the other side. Coils *d* are arranged in the space of each of the pot-shaped pole pieces coaxially to the armature *a* and are connected in such a manner that according to the direction of the alternating flux the force flux emanating from the permanent magnet *g* is amplified at the middle of the pot-shaped pole pieces and at the same time attenuated at the circumference of the pole pieces or inversely, causing the armature *a* to rotate. The movement of the armature is transmitted in known manner to the diaphragm connected to the mouthpiece *i* of the loudspeaker.

I claim:

1. A loudspeaker system, comprising in combination a horseshoe magnet, an armature freely rotatable between the arms of said magnet and having a plurality of radially projecting spoke like arms, two coaxial pot shaped pole pieces, one connected with each arm of said magnet and surrounding said armature, tooth-shaped poles projecting from the middle and edges of the inner side of both of said pole pieces corresponding in number to the number of armature arms and forming a small air gap between the ends and middle portions of said armature arms, said poles being mutually displaced so that a tooth in the middle zone is covered by its coordinate armature arm on one side, whereas the corresponding tooth in the outer zone is covered from the other side, and

coils, one within the free space in each of said pole pieces coaxial with said armature, so connected that according to the direction of the alternating flux the force flux emanating said permanent magnet is amplified at the middle of said pot-shaped pole pieces and at the same time attenuated at the outer portion of said pole pieces or inversely, so that said armature is rotated in one or other direction and is returned into its central position under the permanent attraction of said magnet when no alternating current flows through said coils.

2. A loudspeaker system, comprising in combination, a horse shoe magnet, an armature freely rotatable between the arms of said magnet and having a plurality of radially projecting spoke-like arms and two coaxial pot shaped pole pieces, one connected with each arm of said magnet and surrounding said armature.

3. A loudspeaker system, comprising in combination, a horse shoe magnet, an armature freely rotatable between the arms of said magnet and having a plurality of radially projecting spoke-like arms and two coaxial pot shaped pole pieces, one connected with each arm of said

25

magnet and surrounding said armature, tooth shaped poles projecting from the middle and edges of the inner sides of both of said pole pieces corresponding in number to the number of armature arms and forming a small air gap between the ends and middle portions of said armature arms.

4. A loudspeaker system, comprising in combination, a horse shoe magnet, an armature freely rotatable between the arms of said magnet and having a plurality of radially projecting spoke-like arms and two coaxial pot shaped pole pieces, one connected with each arm of said magnet and surrounding said armature, tooth shaped poles projecting from the middle and edges of the inner sides of both of said pole pieces corresponding in number to the number of armature arms and forming a small air gap between the ends and middle portions of said armature arms, said poles being mutually displaced, so that a tooth in the middle zone is covered by its coordinate armature arm on one side, whereas the corresponding tooth in the outer zone is covered from the other side.

HANS WITTORF.
